UNITED STATES PATENT OFFICE.

ANDREW MOSER, OF HICKMAN, NEBRASKA.

FIRE-ESCAPE.

1,084,162.

Specification of Letters Patent.

Patented Jan. 13, 1914.

Application filed May 15, 1913. Serial No. 767,837.

To all whom it may concern:

Be it known that I, ANDREW MOSER, a citizen of the United States, residing at Hickman, in the county of Lancaster and 5 State of Nebraska, have invented certain new and useful Improvements in Fire-Escapes, of which the following is a specification.

This invention relates to fire-escapes 10 characterized by an endless ladder which is so placed alongside the building as to pass the fire-exits thereof.

It is the object of the present invention to provide a novel and improved ladder 15 structure by means of which the escape from a burning building may be quickly and safely made, a guard being provided which holds the ladder steady and prevents it from swaying.

20 Other objects and advantages of the invention will be pointed out in the detailed description appearing hereinafter, and in order that the invention may be better understood, reference is had to the accompanying drawing in which—

Figure 1 is an elevation of a portion of a building equipped with my improved fire-escape. Fig. 2 is a front elevation of the apparatus. Fig. 3 is a vertical section on 30 the line 3—3 of Fig. 2. Fig. 4 is a horizontal section on the line 4—4 of Fig. 2.

Referring specifically to the drawing the ladder is made up of two endless chains 5 spaced sidewise and connected at regular 35 intervals by crossbars 6 forming the rungs of the ladder. The chains are trained over top and bottom sprocket wheels 7 and 8 respectively journaled on shafts 9 carried by brackets 10 suitably mounted on the wall 40 of the building. The bracket which supports the shaft of the bottom sprocket wheel also has a bearing for a shaft 11 carrying a pinion 12 which is in mesh with a gear wheel 13 on the shaft of said lower sprocket 45 wheel. The shaft 11 carries centrifugal arms 14 equipped with brake shoes 15 at their free ends and adapted to come in contact with the inner surface of a brake drum 16 mounted on the side of the building.

50 When the ladder is in motion, the arms 14 fly outward and force the shoes 15 into frictional contact with the drum 16, whereby the speed of the ladder is automatically checked. An increased weight placed on 55 the ladder tends to increase the speed thereof, whereby the braking action is increased

to retard the motion, the braking action lessening as the speed is reduced. Thus a uniform speed of the ladder is maintained irrespective of the load placed upon it, and it is prevented from traveling too fast for 60 the safety of the occupants thereof.

The ladder is placed at a slight inclination to facilitate its use, and it is equipped at intervals with platforms 17 hinged at 65 their inner ends on the rungs 6 and held in horizontal or supporting position by chains 18 connected at one end to the outer ends of the platform and at their other ends to one of the rungs above the rung which carries the platform. The platforms are free to swing upward, but downward swing is prevented by the chains.

The descending side of the ladder is provided with a guide for preventing swaying 75 thereof. This guide is composed of two angle beams 19 connected by cross braces 20 to form a rigid frame-work. The angle irons are positioned so that the chains 5 lie in the angle thereof, whereby the ladder 80 is prevented from swaying sidewise as well as back and forth, the angle beams providing a firm and rigid support. The frame-work forming the guide is supported by brackets 21 secured to and extending outward from the building. The outer ends of the brackets have depressed portions to space the same from the rungs 6 of the ladder so that the rungs may be grasped without the hands coming in contact with the 85 bracket. For the same reason the cross-braces are bent outward from the angle beams.

The building is shown equipped with balconies 22 having exits 23, and the ladder is 95 so located that the platforms 17 pass the exits one after the other, when the ladder is in motion. Thus a person can easily step from a balcony onto a platform as it passes the same, to be safely carried to the ground, 100 the lower end of the ladder being located sufficiently close to the ground so that the occupant may step off the platform when it reaches the ground, without being tripped. The platform naturally slips away from the 105 occupant thereof when the bottom is reached. As the platforms are pivoted, the lower end of the ladder can be placed close to the ground, the platforms folding back to clear the ground. The angle beams 19 hold the 110 ladder close to the balconies so that the platforms are guided to pass close to the exits,

and said beams terminate a short distance above the ground.

The guides and supports of the ladder also carry a sheet-iron cover 24 extending 5 from the top to the bottom, so that there is no danger of the occupants of the platform having their feet caught in the cross-braces 20.

The ladder can be made of any length to 10 suit the building which is to be equipped therewith, and as the apparatus is simple in construction it can be easily and cheaply installed.

I claim:

15 A fire-escape comprising an endless ladder, top and bottom supports for the ladder to permit travel thereof, a guide for the de-

scending side of the ladder, said guide comprising angle beams in the angle of which the sides of the ladder run, cross braces connecting the angle beams, a cover plate extending between the angle beams over the cross braces, and supporting brackets for the angle beams, the cross braces, the cover plate and the portions of the brackets which 20 lie between the angle beams being spaced from the rungs of the ladder.

In testimony whereof I affix my signature in presence of two witnesses.

ANDREW MOSER.
